UNITED STATES PATENT OFFICE.

JOSEPH E. GAGNON, OF PHILADELPHIA, AND JOHN A. HAWTHORNE, JR., OF CHESTER, PENNSYLVANIA, ASSIGNORS OF ONE-THIRD TO ALFRED S. ORCHARD, OF PHILADELPHIA, PENNSYLVANIA.

PLUMB, LEVEL, AND SQUARE.

1,216,105.

Specification of Letters Patent. Patented Feb. 13, 1917.

Application filed July 22, 1916. Serial No. 110,662.

To all whom it may concern:

Be it known that we, JOSEPH E. GAGNON, a citizen of the United States, residing in the city and county of Philadelphia, State of Pennsylvania, and JOHN A. HAWTHORNE, Jr., a citizen of the United States, residing at Chester, in the county of Delaware, State of Pennsylvania, have invented a new and useful Plumb, Level, and Square, of which the following is a specification.

Our invention consists of an implement or device which is adapted to be converted into a plumb, a level, a square, and an inclinometer; and forms various kinds of squares as a try square, T-square, miter, etc., the novel features being set forth in the claims that follow the specification.

The invention is satisfactorily illustrated in the accompanying drawing, but the important instrumentalities thereof may be varied, as long as they are included in the scope of the claims.

Figures 1, 2, 3 and 4 represent side elevations of a device embodying a plumb, level and square, embodying our invention, the members thereof being in different positions in the several figures.

Fig. 5 represents a longitudinal section on the line $x-x$ Fig. 2.

Fig. 6 represents a transverse section of a portion on the line $y-y$ Fig. 2.

Fig. 7 represents a side elevation of a portion of a modification.

Similar numerals of reference indicate corresponding parts in the figures.

Referring to the drawings.

1 designates a graduated blade in which is the longitudinally-extending slot 2, the latter receiving at one end the screw 3, the head 4 whereof overlaps the walls of said slot, and the shank whereof enters a threaded opening eccentric in the disk 5 in which are lips 6 turned-out from the same and engaging the adjacent edge of the blade 1, thus firmly connecting said disk with said blade.

7 designates a stock which carries the casting of a spirit-bubble 8 firmly secured thereto in any suitable manner, adapting the stock to form a spirit-level as in Figs. 1, 2 and 3.

In one side of what may be termed the

head of the stock which is formed of double walls is the circular opening 9, the wall whereof is freely mounted on the circular disk 5, whereby said stock may be rotated on the latter and so change its angle with respect to the blade 1.

On the end of the screw 3 opposite to the head 4 is the thumb nut 10, whereby the stock 7 may be tightened in the position in which it may be placed on the blade 1, it being noticed that said screw is slidable in the slot 2 of the blade, and thus the stock may be placed at the end of the blade, at the center thereof, or intermediate of its ends, so as to form a try or T-square, a miter, and other kinds of squares, and a protractor as desired, some forms of which are shown in the different figures.

In the stock 7 is the longitudinally-extending slot or recess 11, in which the blade 1 may be received or folded in some of the positions in which the blade and stock may be placed, see Figs. 1 and 5.

The other side of the head 12 of the stock is cut away forming the recess 13 and the diametrical bar 14, said recess allowing said head to rotate around the head 4 of the screw 3 which head 4 projects into said recess, and said bar 14 receives the shank of the screw 15 which enters a threaded opening in the center of the disk 5 and carries the thumb nut 16 which is adapted to tighten the stock on said disk in the position in which either said stock or the blade may be placed with relation to each other.

It is evident that the members of the device may be manipulated to form a plumb or inclinometer of the latter, or convert it into a spirit level, different kinds of squares, a rule, or measure, the latter being due to the graduated blade 1.

Owing to the graduations on the disk 5, the stock 7 may be set with precision thereon, relatively to the desired angle of the latter, so as to be easily read off.

The end of the blade 1 at the adjacent terminal of the slot 2 is rounded as at 17 so that by removing the screw 3 and moving the stock 7 to the full extent of said slot one of the lips 6 may clear said end of the blade and permit the stock to make a full turn on the disk with the screw 15 as its center and

trically in an opening therein, and means for tightening said threaded member in position.

50

5. A blade having a longitudinally-extending slot therein, a stock, a circular member on said blade, the head of said stock being rotatively mounted on said member, a central connection for said blade and member, a threaded member adapted to pass through said slot and engage with the walls thereof and to enter said circular member eccentrically, and a lip on said member adapted to engage the edge of said blade opposite to said threaded member thereby connecting said blade and circular member.

6. A blade, a stock having in its head a recess forming a diametrical bar, a circular member on said blade, said stock being rotatively mounted on said member, means for centrally connecting said member with said bar, a threaded member for eccentrically connecting said circular member with said blade, said threaded member being secured to said blade and having its head freely enter said recess and adapted to limit the rotation of said stock.

7. In a device of the character stated, a blade, a stock, a circular member on said blade, a device for adjustably connecting said stock with said blade, means for pivotally mounting said stock on said circular member, said stock having a head formed of a plurality of walls, between which portions of said blade are movable slidingly and rotatably, one of said walls being rotatively mounted on said circular member, the other wall having therein a recess adapted to receive freely the head of the device that connects said stock with said blade as a stop for limiting the rotation of said stock in its opposite directions on said blade.

JOSEPH E. GAGNON.

JOHN A. HAWTHORNE, JR.
